UNITED STATES PATENT OFFICE

HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS

LACING MACHINE

Application filed April 23, 1928, Serial No. 272,029. Renewed March 10, 1930.

My application Serial No. 105,684, filed April 30, 1926, now Patent No. 1,774,591, dated Sept. 2, 1930, discloses a skein-lacing machine comprising means for dividing a 5 skein into bundles of strands and means for drawing the ends of a lacing around the bundles, one end going over and the other under a given bundle. The means for drawing the ends of the lacing around the bundle 10 consists of two chains. The lacing is brought into proximity to the ends of the chains by a so-called looper, after which the mid-portion of the lacing is moved into engagement with the chains by means of two pivoted inserting-fingers.

After the ends of the lacing have been drawn around the bundle, a pivoted passing-in arm moves the ends of the lacing laterally into operative relation to a knotter that ties 20 the ends of the lacing together.

One of the objects of the present invention is to simplify the means for associating the lacing with the ends of the chains. This object has been attained by dispensing with 25 the inserting-fingers and by adapting the looper and associated parts to place the lacing in direct engagement with the chains.

Another object of the invention is to simplify the means for placing the ends of the 30 lacing in the knotter. This object I have attained by dispensing with the passing-in arm and by utilizing a suction air current to draw the ends of the lacing into the knotter.

35 A further object is to dispense with clamps for holding the lacing in operative relation to the tying bill and the stripper disk, the suction air current being utilized for that purpose.

40 Another object is to simplify the yieldable connection between the chains and the chain-reciprocating means.

In the accompanying drawings,

45 Figure 1 is a fragmental rear elevation of the lacing mechanism, the comb by means of which the skeins are divided into bundles of strands being shown in dotted lines.

50 Fig. 2 is a fragmental view of a tube through which lacing material is conducted

to the mechanism that furnishes lengths of lacing to the lacing chains.

Fig. 3 is a fragmental left-hand end elevation of the machine.

Fig. 4 is a fragmental front elevation of 55 the lacing mechanism.

Fig. 5 is a similar view of the lacing mechanism and the tying mechanism, the parts being shown in a different position from that illustrated in Fig. 4.

Fig. 6 is a transverse vertical sectional view.

Fig. 6^a is a view showing the lacing chains and the looper in the position illustrated in 60 Fig. 4.

Fig. 6^b is a view of certain of the parts shown in Fig. 6^a, looking from the right-hand side of said figure.

Fig. 6^c is a sectional view on line c—c of 65 Fig. 6^a.

Fig. 7 is a view looking from the left-hand side of the knot-tying mechanism, the view being taken in the plane of line 7—7 of Fig. 8.

Fig. 8 is a plan view of the knot-tying 75 mechanism and certain related parts.

Fig. 8^a is a section on line a—a of Fig. 8.

Figs. 9 and 10 are perspective views of the knot-tying mechanism in different positions.

Fig. 11 is a plan view of the knot-tying 80 mechanism with certain parts in section.

Figs. 12, 13 and 14 illustrate a yieldable connection between the chains and the chain-reciprocating means, and a portion of the means for effecting stoppage of the machine 85 in the event that the movement of the chains is obstructed.

The present invention has been disclosed in connection with a machine of the general type shown in said application Serial No. 105,684, but it is to be understood that the invention is capable of use in connection with 90 other types of skein-lacing mechanisms.

The present drawings disclose a lacing mechanism adapted to travel step by step 95 along a fly (not shown) carrying a plurality of skeins. After lacing the first skein the mechanism progresses step by step across the machine until the skeins have all been laced.

The means for dividing the skeins into 100

bundles of strands S' (Figs. 4 and 5) may be of any preferred construction. In Figure 1 I have indicated in dotted lines a comb similar to that fully disclosed in application Serial No. 105,684. 1 are the skein spacers and 2 are the comb teeth or skein piercers. However, the present invention is adapted for use in connection with a machine wherein the skein is wound in such a manner that openings are produced therein to receive the lacing.

The lacing mechanism is mounted upon a carriage C which is arranged to travel back and forth along the fly and below the comb. The carriage is provided with wheels 3 (Fig. 3) which run upon tracks 4. The carriage comprises an indexing bar 5 (Fig. 1) which may be guided as disclosed in application Serial No. 105,684. The carriage further comprises an upright 6 which is secured to the forward portion of the carriage by means of stay rods 7.

The means for passing a lacing cord around the bundles comprises two flexible members (herein shown as consisting of chains) which are guided in symmetrical wavy or tortuous passageways formed in a lower conduit block 8 and an upper conduit block 9. As shown in Fig. 1, the upper conduit block 9 is secured to the forward end of a rod 10 which is secured to the upper portion of the upright 6. The conduit block 9 travels within the series of skeins and through a passageway 11 (Fig. 3) formed in and extending longitudinally of the comb. The rod 10 normally holds the conduit block 9 up out of the horizontal plane of the side of the skein which is being laced, said block being depressed into engagement with successive skeins by means fully disclosed in application Serial No. 105,684.

The conduit block 8 is secured to a slide 12 which is guided in the framework of the carriage C for vertical reciprocation. On the lower portion of the slide 12 is a roller 13 (Fig. 5) that runs in the cam groove 14 of a spur gear wheel 15. Said gear wheel is driven in the manner disclosed in application Serial No. 105,684. The reciprocation of the slide 12 carries the conduit block 8 into and out of operative position. Compare Figs. 4 and 5.

The lacing chains hereinbefore referred to are indicated at 16 in Figs. 4 and 12. The chains are reciprocated into and out of the conduit blocks by means of a car 17 (Figs. 12 and 13), said car having rollers 18 that run in guideways 19 in the slide 12. A pitman 20 (Fig. 4) connects the car 17 to a crank 21 that rotates with the spur gear wheel 15. In the slide 12 are two parallel undercut grooves 12^a (Figs. 4, 8, 12 and 13) to receive the chains 16, said grooves communicating with the channels in the conduit block 8, as shown in Fig. 4.

In order to prevent breakage in the event that the movement of the chains is obstructed, the chains are yieldingly connected to the car

17 by means shown in Figs. 12, 13 and 14. A slide 22 is connected to the lower end of each chain. In each of said slides is a notch 23 to receive arms 24 formed integral with a hub 25. The hub 25 is fixed to a shaft 26 which is pivotally supported on the car 17. Rigid with the shaft 26 is an arm 27 having a wedge-shaped projection 28 thereon, said projection being adapted to engage in a notch 29 formed in a block 30. The block 30 is secured to the arm 31 of a lever that is pivoted on the car 17 at 32. The other arm of the lever 31 constitutes a clamping member 33 which is adapted to coact with a clamping member 34 on the car 17 to clamp a safety stopping bar 35. 36 is an expansive spring that normally holds the block 30 pressed against the projection 28. In case the movement of the chains is obstructed the continuing travel of the car 17 causes the shaft 26 to turn to carry the arm 27 away from the block 30, the spring 36 yielding to allow the tapered projection 28 to leave the notch 29. As soon as said projection is out of the notch, the spring 36 moves the clamping member 33 into clamping engagement with the rod 35, whereupon the machine is stopped in the manner disclosed in application Serial No. 105,684.

On the free end of each chain 16 is a hook 37 (Fig. 6^a). The means for placing a lacing in engagement with said hooks comprises a looper 38 (Fig. 6) rigidly secured to the car 17 by means of a bracket 39. The looper 38 has two upwardly directed fingers 40 which are spaced apart so as to pass at opposite sides of the pair of chains 16. (see Fig. 6^b). In the upper ends of the fingers 40 are notches 41. Means of any preferred character, as, for example, that disclosed in application Serial No. 105,684, is provided to hold lacing material stretched in the path of upward movement of the fingers 40. In Fig. 6, lacing material L is shown as held extended between a clamp 42 and a guide eye 43. The guide eye 43 is formed in a tube 43^a mounted on the carriage C. The lacing material is drawn through the tube 43^a, the latter serving to protect the lacing material from fouling on parts of the machine. In the upward stroke of the looper 38 the notched ends of the fingers 40 engage the lacing L between the clamp 42 and the guide eye 43 and draw a bight of lacing material up to the lacing chain. Lacing material is drawn through the guide eye 43 as the lacing is carried up to the chains.

Two plates 44 (Fig. 6^c) are secured to the conduit block in vertical position between the paths of the looper fingers 40 and at opposite sides of the vertical planes of the chains 16. As shown in Fig. 6^a, the edges of said plates are so shaped that after the lacing has passed the hooks 37, it is cammed or deflected nearer the chains and thus placed in position to be taken by the hooks.

5 A rib 45 (Fig. 6^a) on the conduit block 8 extends between the vertical planes in which the chains 16 travel and serves as an abutment to hold or detain the mid-portion of the lacing while the ends of the latter are being drawn by the hooks 37 around the bundles S'. When the conduit blocks 8 and 9 separate (as shown in Fig. 5), the rib 45 is withdrawn downwardly away from the mid-portion of the lacing.

10 At the time the looper delivers the lacing to the lacing chains, as shown in Figs. 6^a and 6^b, the looper clamp 42 (Fig. 6) opens, and a shear 46 acts to sever the lacing, as explained in application Serial No. 105,684.

15 Since the mid-point of the lacing is in contact with the rib 45, and the chain hooks 37 engage the lacing on opposite sides of and close to said rib (as shown in Fig. 6^c), it will be seen that when the chains are drawn out of the passages in the conduit blocks they will draw the legs of the bight of lacing around the bundles S' and will deliver the ends of the lacing to the opposite end of the conduit blocks. While the chains are being retracted, as just described, the mid-point of the lacing is held by the rib 45, and the legs of the bight slip through the hooks 37. As the chains travel through the conduit blocks they draw the lacing around the bundles of the skein and continually shorten the trailing ends of the lacing; and when the chains arrive in such position that they are wholly within the chain-guiding grooves 12^a, the ends of the lacing will have become free. When the ends of the lacing have been delivered into the grooves 12^a, the conduit blocks are caused to separate. When the lower conduit block 8 descends, the rib 45 slides away from the mid-point of the lacing and the latter engages the first bundle of the skein.

20 In the present embodiment of the invention, the knot-tying mechanism is not reciprocated up and down, but is located as close as practicable to the horizontal plane of the bundles S'. The form of knotter herein shown comprises a rotary tying bill 47 (Fig. 11) similar to the one disclosed in the patent to Burt A. Peterson No. 959,592, dated May 31, 1910. The shaft 48 of the tying bill is horizontally disposed and is continuously rotated by means of a pinion 49 on said shaft meshing with a gear wheel 50 on a vertical shaft 51. Below the tying bill is a suction conduit 52 which is connected by means of a tube 53 to an exhaust (not shown). The conduit 52 extends transversely of the tying bill shaft 48, as shown in Fig. 11. On the vertically reciprocating slide 12 is a short tube 54 (Figs. 5 and 8) which communicates with the chain-guiding passages 12^a. The tube 54 is of such length and so positioned on the slide 12 that when the latter is in its lowermost position, as shown in Figs. 5 and 8^a, the tube 54 is aligned with and close to

the end of 55 of the conduit 52. In the upper wall of the tube 54 is a slot 56 (Fig. 8) which communicates with the chain-guiding passages 12^a by means of a flaring throatway 57. The slot 56 is in the vertical plane of a slot 58 in the upper wall of the conduit 52. As shown in Fig. 11, the slot 58 continues past the tying bill 47. Pivotally mounted on the conduit 52 between the tying bill 47 and the lacing mechanism is a sleeve 59 which is slotted or cut away in its upper portion. The edge 60 (Fig. 11) of said slot is curved so that when the sleeve 59 is turned in the clockwise direction (as viewed in Fig. 9), the slot 58 in the conduit 52 will be gradually closed or covered, beginning at a point adjacent to the tying bill, and will be gradually uncovered when the sleeve 59 turns in the opposite direction. The sleeve 59 is arranged to be oscillated by means of an arm 61 which is rigid with said sleeve and carries a roller that lies in the groove of a cam 62 which is fixed on the shaft 51.

25 Above the tying bill 47 are two parallel horizontal plates or abutments 63 and 64. 65 is a stripper disk mounted for rotation in a horizontal plane between the plates 63 and 64, said disk being driven from the shaft 51 by means of the gear train 66 (Fig. 7). In the edge of the plate 64 is a notch 67 which cooperates with the disk 65 in the tightening of the knot and the stripping of the latter from the tying bill 47.

30 Referring to Fig. 5 which shows the car 17 in its lowermost position, wherein the chains are wholly within the grooves 12, the vertically reciprocatory structure 8 and 12 also being in its lowermost position wherein the tube 54 is in register with the suction conduit 52. The suction current in the conduit 52 draws the ends of the lacing out of the grooves 12^a and through the throatway 57 into the slot 56. The edge 60 of the oscillatory sleeve 59 serves as a timing cam to prevent the ends of the lacing from being drawn into the rear portion of the slot 58 until the constantly rotating tying bill is in position to receive them. When the tying bill is in the position shown in Fig. 5, the sleeve 59 allows the ends of the lacing to pass laterally into the rear or inner end of the slot 58. In the revolution of the tying bill in the counter-clockwise direction (as viewed in Figs 5 and 9), the bill engages the lacing and ties a knot in the manner fully described in said Peterson patent. As the tying bill is completing the formation of the knot, the stripper disk 65 engages the lacing at a point between the plates 63 and 64, the notch 67 assisting to hold the lacing for the stripping operation.

35 By simplifying the means for associating the lacing with the chains 16 and the means for transferring the lacing from the chains to the knotter, I have effected a substantial reduction in cost of manufacture of the ma-

chine. The safety mechanism disclosed in application Serial No. 105,684 for effecting stoppage of the machine in the event of interference with the movement of the passing-in arm is no longer necessary. By utilizing the suction current for holding the lacing in the knotter, it has been possible to dispense with the clamps shown for that purpose in said application.

10 Although I have described the present embodiment of the invention with considerable particularity, it should be understood that various constructional and operative rearrangements may be made without departing from the spirit and scope of the invention as set forth in the following claims.

I claim as my invention:

1. In a skein-lacing and lace-tying mechanism, the combination of a vertically reciprocatory structure having channels therein, lacing members reciprocable in said channels, a tube fixed to said structure and communicating with said channels, a stationary knotter comprising a rotary tying bill, two guide plates above the tying bill and a rotary stripper disk between said plates, a suction conduit below said tying bill and arranged to register with said tube in one position of the latter, the upper walls of said tube and conduit being longitudinally slotted to permit the suction current to draw the ends of the lacing from said channels and through said slots into operative relation to said tying bill and plates, and a reciprocatory member arranged to control the slot in the suction conduit to time the movement of the ends of the lacing into operative relation to the tying bill.

2. In a skein-lacing and lace-tying mechanism, the combination of a vertically reciprocatory channeled structure, lacing means reciprocable in said channeled structure, a tube fixed to and communicating with said channeled structure, a stationary knotter, a suction conduit below the knotter and arranged to register with said tube in one position of the latter, the upper walls of said tube and conduit being longitudinally slotted to permit the suction current to draw the ends of the lacing from said channeled structure and through said slots into operative relation to the knotter, and means to control the slot in the suction conduit to time the movement of the ends of the lacing into operative relation to the knotter.

3. In a skein-lacing and lace-tying mechanism, the combination of a vertically reciprocatory channeled structure, lacing means reciprocable in said structure, a tube fixed to and communicating with said channeled structure, a stationary knotter comprising a rotary tying bill, two guide plates above the tying bill and a rotary stripper disk between said plates, and a suction conduit below said tying bill and arranged to register with said

tube in one position of the latter, the upper walls of said tube and conduit being longitudinally slotted to permit the suction current to draw the ends of the lacing from said channels and through the slots into operative relation to said tying bill and plates.

4. The combination of a vertically reciprocatory lacing means, a stationary knotter comprising a rotary tying bill, two guide plates above the tying bill and a rotary stripper disk between said plates, a suction conduit below said tying bill and arranged to receive the lacing from said lacing means in one position of the latter, the upper wall of said conduit being longitudinally slotted to permit the suction current to draw the ends of the lacing through the slot into operative relation to said tying bill and plates, and means to control the slot in the suction conduit to time the movement of the ends of the lacing into operative relation to the tying bill.

5. In a skein-lacing and lace-tying mechanism, the combination of lacing members, a tube adjacent to the path of said members, a knotter, and a suction conduit adjacent to the knotter and adapted to register with said tube, said tube and conduit being slotted to permit the suction air current to draw the ends of the lacing through said slots and into operative relation to the knotter.

6. The combination of lacing mechanism, a tube adjacent to said mechanism, a knotter, a suction conduit adjacent to the knotter and adapted to register with said tube, said tube and conduit being slotted to permit the suction air current to draw the ends of the lacing through said slots and into operative relation to the knotter, and means to control the passage of the lacing through the slot in said conduit.

7. In a skein-lacing and lace-tying mechanism, the combination of lacing means, a tying bill, a suction conduit below the tying bill arranged to receive the lacing from said lacing means, said conduit being slotted to permit the suction air current to draw the ends of the lacing laterally through the slot and into operative relation to the tying bill.

8. In a skein-lacing and lace-tying mechanism, the combination of lacing means, a knotter, means forming a conduit extending between the knotter and said lacing means, said conduit-forming means being slotted to permit the suction air current to draw the ends of the lacing laterally through the slot and into operative relation to the knotter.

9. In a skein-lacing mechanism, two lacing members having hooks, two reciprocatory fingers arranged to pass at opposite sides of said hooks and carry a bight of lacing thereto, and two stationary plates located between the paths of said fingers and at opposite sides of said hooks, said plates having

cam edges adapted to deflect the lacing into position to be taken by said hooks.

10. In a skein-lacing mechanism, lacing means including hooks, two reciprocatory fingers arranged to pass at opposite sides of said hooks and carry a bight of lacing thereto, and stationary means located between the paths of said fingers and at opposite sides of said hooks and acting upon the lacing as the latter is being moved by said fingers, to deflect the lacing into position to be taken by said hooks.

11. In a skein-lacing mechanism, lacing means including hooks, means to carry a lacing to the hooks, two stationary plates located at opposite sides of said hooks, said plates having cam edges adapted to deflect the lacing into position to be taken by said hooks.

20. 12. In a skein-lacing mechanism, lacing means including hooks, means to carry a bight of lacing to the hooks, and two stationary members located at opposite sides of said hooks, said members acting upon the lacing as the latter is being moved by the second-mentioned means to deflect the lacing into position to be taken by said hooks.

13. In a skein-lacing machine, the combination of a guiding structure, two lacing chains movable in said structure, a slide connected to each chain, said slide being notched, a reciprocatory car, a lever pivoted on said car, said lever having two arms engaging in the notches in said slides, and a stop-motion member yieldingly engaging another arm of said lever to hold said lever normally stationary with reference to said car.

14. The combination of a rotary tying bill, two abutments at one side of the tying bill, a stripping member operating between said abutments, and a suction conduit extending transversely of the axis of the tying bill at the opposite side thereof, said conduit having a longitudinal slot in the side toward the tying bill to permit the suction current to draw the strands to be tied across the tying bill and said abutments.

15. The combination of a rotary tying bill, stripping means at one side of the bill, a suction conduit at the opposite side of the bill, said conduit extending transversely of the axis of the bill and having a longitudinal slot in the side toward the bill to permit the suction current to draw the strands to be tied into operative relation to the bill and the stripping means, and means to control the passage of the strands along the slot.

In testimony whereof, I have hereunto affixed my signature.
